WILLOUGHBY STATHAM SMITH, OF BENCHAMS, NEWTON POPPELFORD, AND NORMAN WILLIAM McLACHLAN, OF LONDON, ENGLAND.

CABLE TELEGRAPHY AND THE LIKE.

Application filed December 27, 1927, Serial No. 242,302, and in Great Britain August 23, 1926.

This invention relates to cable telegraphy and the like, and especially to cable telegraph receivers employing thermionic valves.

5 The invention has for object to provide means for eliminating or minimizing interference, due to very low frequency disturbances, especially slowly varying earth currents in a submarine cable telegraph system.

In carrying out this invention an impedance comprising two or more sections of substantially different reactance is interposed in the common path of the signal currents 15 and the low frequency disturbances, and a compensating thermionic valve or valves is or are associated on the input side with one of the said sections, and on the output side with the thermionic valve receiver, whereby 20 a voltage change in the common path, due to a disturbance, is substantially compensated by a voltage change of opposite effect applied to the thermionic receiver by the compensating thermionic valve or valves.

25 Preferably the impedance inserted in the common path comprises two sections, one of which is a substantially pure resistance, and the other a capacitative and resistive impedance of relatively high alternating current resistance at disturbance frequency and negligible alternating current resistance at signal frequency.

The invention is illustrated in the accompanying diagrammatic drawings, wherein:

30 Figure 1 illustrates a receiving circuit arrangement embodying the principles of our invention; Fig. 2 shows a shaping network employed in the circuit arrangement of our invention; and Fig. 3 shows a receiver circuit embodying the principles of our invention and compensated for voltage fluctuations.

35 Referring to Fig. 1, which shows one way of carrying out the invention, the cable 1 is connected to earth through a line resistance 2, a section 2' of which, is shunted by a capacity 3 of such value that the impedance of the said section and shunt capacity is very low at signal frequency and high at the 40 frequency of disturbances such as slowly changing earth currents. The grid 4 of a compensating triode 5 is connected to the cable 1, the anode circuit of the said triode being completed through a choke 6, an anode 45 battery 7 and a resistance 8 (which may be

shunted by a condenser to reduce the effect of signal frequencies) to the cathode 9.

The capacity-shunted section 2' of the line resistance is located at the cable end of the resistance 8, and the grid and cathode of a 50 compensating valve 5 are directly connected there across, the grid and cathode of a receiving valve 11 being connected respectively to a tapping point 12 which is preferably variable as shown, upon the said resistance 65 3, and to the earthed end of the line resistance 2. R is the receiving device and 11^a the plate battery for the valve 11. Obviously any amplifying arrangement may be interposed in known manner between the valve 70 11 and the receiver R.

If desired a shaping network may be interposed between the line resistance 2 and the cable, and the compensating triode 5 may be replaced by a plurality of triodes 75 in parallel.

It will be seen that a very low frequency disturbance will give rise to a voltage drop across the capacity-shunted section 2' of the line resistance, the said voltage drop giving 80 rise to a change of current in the anode circuit of the compensating triode 5. Owing to this change of current there will be caused a change of voltage drop across the resistance 8 in the said anode circuit, and 85 therefore a change in the potential between grid and cathode of the thermionic receiver 11, the last mentioned change serving to compensate for the change in the potential applied by the disturbance directly to the 90 grid of the receiver valve. The compensating valve will, however, be substantially unaffected by signals, owing to the action of the shunting condenser, and to the choke 95 in the anode circuit of the said valve.

Where a shaping network is employed, the line resistance and shunt capacity may, if desired, form part thereof, additional inductance and/or resistance and/or capacity being connected in parallel with the said line resistance. Such an arrangement is illustrated in Figure 2, in which 13, 14 are added elements forming a shaping network, and 15 a condenser shunting the resistance 8 and serving to reduce the effect of signal 100 frequencies.

If desired the primary of a transformer, so designed as not to operate at frequencies as low as those of the disturbances, may be connected in the anode circuit of the com- 110

pensating triode, the secondary thereof being connected in the anode or the grid circuit of the main valve. This transformer serves to adjust for any over-compensation, due to 5 high frequency voltage fluctuations. Such an arrangement is illustrated in Figure 3, in which 10 is the transformer serving to adjust for over-compensation. A high resistance may be shunted across the secondary 10 of the transformer and/or a resistance may be associated with the primary thereof in order to adjust for amplitude and phase. It will be seen that any high frequency voltage fluctuations which may occur in the 15 anode circuit of the valve 5 will cause the transformer 10 to apply a compensating potential to the grid of the said valve.

Obviously, the input to the compensating valve may, if desired, be amplified by any 20 suitable means, such as a resistance coupled valve. Referring to Figure 1, if a disturbance has arrived through the cable 1, then, owing to the fact that the impedance of the section 2'3 (which is very low at signal frequency) is high at disturbance frequencies, there will be a voltage (higher than that which would be set up by a signal of corresponding strength) generated across the said section 2'3. This voltage, applied between 25 the grid and filament of the tube 5, will cause a variation in the plate current flowing in the plate circuit of this tube, and therefore a variation in the current flowing through the resistance 8.

35 Since the voltage across a resistance R , through which a current I flows, is given by the product IR , there will obviously be a change in the voltage applied to the grid of the valve 11, said change of course serving 40 to compensate for the change of voltage across the section 2'3, to which the change of voltage in the resistance 8 was due. This compensating cycle, as it may be termed, does not occur with signal voltages, since the impedance of the section 2'3 is low at signal 45 frequencies.

50 While we have described our invention in certain preferred embodiments, we desire that it be understood that modifications may be made and that no limitations upon the invention are intended other than are imposed by the scope of the appended claims.

55 What we claim is:—

1. In a cable telegraph or the like receiver, the combination of an impedance located in the common path of signal currents and low frequency disturbances, said impedance comprising a plurality of sections whose reactances at a given frequency are different, and 60 means for applying to a receiving device a compensating voltage change of opposite effect to a voltage change applied thereto by a disturbance, said means comprising thermionic means associated on the input side

with one of said sections and on the output 65 side with said receiving device.

2. In a cable telegraph or the like receiver, the combination of an impedance located in the common path of signal currents and low frequency disturbances, said impedance 70 comprising two sections constituted respectively by a resistance and a resistance shunted capacity, and means for applying to a receiving device a compensating voltage change of opposite effect to a voltage change 75 applied thereto by a disturbance, said means comprising thermionic means associated on the input side with one of said sections and on the output side with said receiving device.

3. In a cable telegraph or the like receiver, the combination of an impedance located in the common path of signal currents and low frequency disturbances, said impedance comprising two sections constituted respectively by a resistance and a 80 resistance shunted capacity, and means for applying to a receiving device a compensating voltage change of opposite effect to a voltage change applied thereto by a disturbance, said means comprising a compensating thermionic valve whose grid and 85 cathode are connected across a capacity shunted resistance at the "cable" end of said impedance, the input terminals of said receiving device being connected between a 90 point in the anode circuit of said valve and the "earth" end of said impedance.

4. In a cable telegraph or the like receiver, the combination of an impedance located in the common path of signal currents and low frequency disturbances, said impedance comprising a shaping network 100 and a plurality of sections whose reactances at a given frequency are different, and means for applying to a receiving device a compensating voltage change of opposite effect to a voltage change applied thereto by a disturbance, said means comprising 105 thermionic means associated on the input side with one of said sections and on the output side with said receiving device.

5. In a cable telegraph or the like receiver, the combination of an impedance located in the common path of signal currents and low frequency disturbances, said impedance comprising a shaping network and two sections constituted respectively by a resistance and a resistance shunted capacity, and means for applying to a receiving device a compensating voltage change of 110 opposite effect to a voltage change applied thereto by a disturbance, said means comprising thermionic means associated on the input side with one of said sections and on the output side with said receiving device.

6. In a cable telegraph or the like receiver, the combination of an impedance located in the common path of signal cur-

rents and low frequency disturbances, said impedance comprising a shaping network and two sections constituted respectively by a resistance and a resistance shunted capacity, and means for applying to a receiving device a compensating voltage change of opposite effect to a voltage change applied thereto by a disturbance, said means comprising a compensating thermionic valve 5 whose grid and cathode are connected across a capacity shunted resistance at the "cable" end of said impedance, the input terminals of said receiving device being connected between a point in the anode circuit of said valve and the "earth" 10 end of said impedance.

7. In a cable telegraph or the like receiver, the combination of an impedance located in the common path of signal currents and low frequency disturbances, said impedance comprising a plurality of sections whose reactances at a given frequency are different, means for applying to a receiving device a compensating voltage 20 change of opposite effect to a voltage change applied thereto by a disturbance, said means comprising thermionic means associated on the input side with one of said sections and on the output side with said receiving device, and means for adjusting for over-compensation 25 said last mentioned means, comprising a transformer inoperative at low or disturbance frequencies and operative at higher frequencies associated with the output of said thermionic means and the input of said receiving device.

8. In a cable telegraph or the like receiver, the combination of an impedance located in the common path of signal currents and low frequency disturbances, said impedance comprising two sections constituted respectively by a resistance and a resistance shunted capacity, means for applying to a receiving device a compensating voltage change of opposite effect to a voltage change applied thereto by a disturbance, said means comprising thermionic means associated on the input side with one of said sections and on the output side with 40 said receiving device, and means for adjusting for over-compensation said last mentioned means, comprising a transformer inoperative at low or disturbance frequencies and operative at higher frequencies associated with the output of said thermionic means and the input of said receiving device.

55 9. In a cable telegraph or the like receiver, the combination of an impedance located in the common path of signal currents and low frequency disturbances, said impedance comprising two sections constituted respectively by a resistance and a resistance shunted capacity, means for applying to a receiving device a compensating

voltage change of opposite effect to a voltage change applied thereto by a disturbance, said means comprising a compensating thermionic valve whose grid and cathode are connected across a capacity shunted resistance at the "cable" end of said impedance, the input terminals of said receiving device being connected between a point in the anode circuit of said valve and the "earth" 70 end of said impedance, and means for adjusting for over-compensation, said last mentioned means, comprising a transformer inoperative at low or disturbance frequencies and operative at higher frequencies associated with the output of said thermionic means and the input of said receiving device.

10. In a cable telegraph or the like receiver, the combination of an impedance located in the common path of signal currents and low frequency disturbances, said impedance comprising a shaping network and a plurality of sections whose reactances at a given frequency are different, means for applying to a receiving device a compensating voltage change of opposite effect to a voltage change applied thereto by a disturbance, said means comprising thermionic means associated on the input side with one of said sections and on the output side with said receiving device, and means for adjusting for over-compensation 85 said last mentioned means, comprising a transformer inoperative at low or disturbance frequencies and operative at higher frequencies associated with the output of said thermionic means and the input of said receiving device.

11. In a cable telegraph or the like receiver, the combination of an impedance located in the common path of signal currents and low frequency disturbances, said impedance comprising a shaping network and two sections constituted respectively by a resistance and a resistance shunted capacity, means for applying to a receiving device a compensating voltage change of opposite effect to a voltage change applied thereto by a disturbance, said means comprising thermionic means associated on the 90 input side with one of said sections and on the output side with said receiving device, and means for adjusting for over-compensation said last mentioned means, comprising a transformer inoperative at low or disturbance frequencies and operative at higher frequencies associated with the output of 95 said thermionic means and the input of said receiving device.

12. In a cable telegraph or the like receiver, the combination of an impedance located in the common path of signal currents and low frequency disturbances, said impedance comprising a shaping network and two sections constituted respectively by 100

a resistance and a resistance shunted capacity, means for applying to a receiving device a compensating voltage change of opposite effect to a voltage change applied thereto by a disturbance, said means comprising a compensating thermionic valve whose grid and cathode are connected across a capacity shunted resistance at the "cable" end of said impedance, the input terminals of said receiving device being connected between a point in the anode circuit of said

valve and the "earth" end of said impedance, and means for adjusting for over-compensation said last mentioned means, comprising a transformer associated with the output of said thermionic means and the input of said receiving device. ¹⁵

In testimony that we claim the foregoing as our invention we have signed our names this ninth day of December 1927.
